JUG

Max Ries, Chicago, Ill., assignor to Continental Specialties Company, Inc., Chicago, Ill.

Filed Feb. 16, 1971, Ser. No. 115,901

Term of patent 14 years

Int. Cl. D9—01

U.S. Cl. D9—50

FIG. 1

FIG. 2

FIG. 3

FIG. 4

FIG. 1 is a perspective view of a jug, showing my new design;

FIG. 2 is a partial side view, as seen from the right;

FIG. 3 is a top plan view thereof; and

FIG. 4 is a cross section taken on the horizontal plane represented by the lines 4—4 in FIG. 1.

I claim:

The ornamental design for a jug, as shown.
